UNITED STATES PATENT OFFICE.

ARTHUR GUY ENOCK, OF HAILSHAM, ENGLAND, ASSIGNOR TO BURLECTAS LIMITED, OF LONDON, ENGLAND.

AIR OR GAS COMPRESSOR.

Application filed February 5, 1926, Serial No. 86,323, and in Great Britain April 14, 1925.

This invention relates to single acting air or gas compressors constructed with one or more cylinders disposed vertically, horizontally or at an inclination thereto provided 5 with suction delivery valves and suction exhaust passages.

According to the invention to ensure large valve areas and slight valve lifts and enable the compressor to be driven at a high speed 10 the suction and discharge passages are fitted with a number of relatively small valves disposed in a ring or circle or in concentric circles or with a single ring disc valve around each cylinder, the suction valves preferably 15 in the end of the cylinder body and the delivery valves in the cylinder head, though this construction may be reversed, or both sets of valves may be in the cylinder body or both sets may be in the cylinder head.

20 The invention will be fully described with reference to the accompanying drawings.

Fig. 1 is a side elevation, part section of a three cylinder mono-block compressor showing the invention applied thereto.

25 Fig. 2 is a sectional plan on line 2—2 Fig. 1.

Fig. 3 is a transverse section on line 3—3 Fig. 2.

30 Fig. 4 is a plan of a three cylinder compressor with separate cylinders.

Figs. 5 to 11 are sectional elevations of various forms of the invention.

Fig. 12 is a side elevation of Fig. 11.

Fig. 13 is a plan of valve seating plate H.

35 Fig. 14 is a plan of cylinder head from below showing suction passages E and delivery passages F.

Fig. 15 is a sectional elevation of another disposition of the invention.

40 Fig. 16 is a sectional elevation of another disposition of the invention.

The compressor may be of ordinary single acting type with one or more cylinders either 45 separately constructed or of mono-block construction and according to the invention the suction valves A comprise a number of small valves to act simultaneously disposed in a circle around the cylinder and the delivery valves B preferably similarly comprise a number of small valves disposed in a circle concentric with the valves A though in some modifications a single centrally placed delivery valve B¹ or suction valve A¹ 50 may be employed. The valves A and B may be ball valves as shown or of any other de-

sired shape such as thimble, mushroom, disc or ring disc.

In the construction shown in Figs. 1, 2 and 3 the invention is shown applied to a three cylinder mono-block compressor. The suction valves A are disposed in a circle around the cylinder end C and the delivery valves B are disposed in a concentric circle in the cylinder head D. The valves A are fitted in recesses a in the cylinder end and held upwards by springs a¹ against a seating on the underside of the cylinder head D and the delivery valves B are mounted in recesses b in a removable block B² and held against seats therein by springs b¹ the block B² being held in position by a spring b².

The suction port or passage E and the delivery port or passage F are both formed in the cylinder head D disposed annularly around the circles of valves and the passages leading therefrom may be of triangular or other shape. The compact arrangement (see Fig. 2) of two triangular passages e and f, the sides of the cylinders C receiving the suction and delivery gases respectively 80 from three cylinders, is at present preferred where mono-block cylinders are used, but separate pockets may be cast on the sides of the cylinders opposite each port with separate connections. The suction valves A open 85 downward on the suction stroke the gas entering the cylinder C through the annular space or slot c between the cylinder body and the cylinder head D and the delivery valves open upwards on the compression stroke of 90 the piston.

In the construction shown in Fig. 4 a three cylinder compressor is shown with separate cylinders C the suction passages and delivery passages being connected to pipes E¹ and F¹ 95 external to the cylinders.

In the construction shown in Fig. 5 the suction valves A are disposed in a circle around the end of the cylinder C opening downwards with seats on the underside of the cylinder head D and the delivery valves B opening upwards disposed in a concentric circle in the cylinder head D. The valves A are fitted in recesses a in the cylinder end and held upwards by springs a¹ against their seats. The valves B are mounted in recesses b in a removable block B² and held against seats therein by springs b¹ the block B² being held in position by a spring b². The suction port or passage E is formed in the cylinder 110

head and connected to the inlet pipe E^1 and the delivery port or passage is connected to the outlet pipe F^1 .

The suction valves A open downwards on the suction stroke the gas entering the cylinder C through the annular space or slot c between the cylinder body and the cylinder head D, the delivery valves open on the compression stroke.

- 10 In the construction shown in Fig. 6 the suction valves A are annularly disposed in recesses a around the end of the body of the cylinder C as in Fig. 1. The springs a^1 and the valves A may each be placed in a cup or 75 light thimble a^2 to enable the rapid removal and replacement of the spring and valve in case of their action being interferred with by foreign matter. The delivery valve B^1 comprises a single centrally disposed ball B^1 held down to its seat B^{11} by spring b^1 in the removable block B^2 which is held in position by the spring b^2 . The suction passages E and the delivery passage F are formed in the cylinder head D. The suction valves A 80 open downwards on the suction stroke the gas entering the cylinder C through the annular space or slot c between the cylinder body and the cylinder head and the delivery valve B^1 opens upward on the compression 85 stroke of the piston.

In the construction shown in Fig. 7 the suction valves A are disposed in a circle opening downwards fitted into recesses a in the end of the cylinder body and held 90 against seats on the underside of the cylinder head D by springs a^1 . The delivery valve B^5 comprises a single centrally disposed valve of hollow type provided with gas passages through it, held down to its seat by a spring. The suction passage E is formed in the cylinder head D and connects with an auxiliary suction passage E^2 in the cylinder body and inlet pipe E connected thereto. The delivery passage F is 95 formed in the cylinder head and connects with the outlet pipe F^1 . The suction valves open downward on the suction stroke the gas entering the cylinder C through the annular space or slot c between the cylinder body and the cylinder head D and the delivery valve B^5 opens upward on the compression 100 stroke.

In the construction shown in Fig. 8 the suction valves A are disposed in a circle 105 opening upwards fitted into recesses a in the end of the cylinder body and held against seats therein by springs a^1 in recesses in the cylinder head. The delivery valve B^4 comprises a mushroom valve 110 mounted in a block B^4 and held to its seat by a spring b^1 . The suction passage E is formed in the cylinder body and is connected with the inlet pipe E^1 . The delivery passage F is formed in the cylinder head D 115 and connects with the outlet pipe F^1 .

The suction valves A open upwards on the suction stroke the gas entering the cylinder C through the annular space or slot c between the cylinder body and the cylinder head and the delivery valve B^4 opens upwards on the compression stroke.

In the construction shown in Fig. 9 the delivery valves B^6 are disposed in a circle opening downwards fitted into recesses a in the end of the cylinder body and held 75 against seats by springs a^3 . The suction valve A^2 comprises a single centrally disposed valve fitted in the cylinder head D opening downward and held up to its seat by a spring a^4 . The suction passage E is 80 deformed in the cylinder head D and the delivery passage F is formed in the cylinder body and connects with the outlet pipe F^1 .

The suction valve A^2 opens downwards on the suction stroke delivering the gas 85 direct into the cylinder and the delivery valves open on the compression stroke the gas being delivered through the annular space or slot c between the cylinder body and the cylinder head to the outlet pipe F^1 .

In the construction shown in Fig. 10 the delivery valves B^7 are disposed in a circle opening upwards fitted into recesses in the cylinder head D and held against seats 90 therein by springs b . The suction valve A^3 95 comprises a centrally disposed valve fitted in the cylinder head D and opening downwards and held up to its seat by springs a^4 . The suction valve A^3 is formed of two concentric valves, the inner seating upon the outer, and adapted to open before it; two springs a^4 being employed for closing the double seated valve. The suction passage E is formed in the cylinder head D and also the delivery passage F. The delivery pipe 100 F^1 and the inlet pipe are connected to the cylinder head. The suction valve A^3 opens downwards on the suction stroke, delivering the gas direct into the cylinder and the delivery valves B^7 open upwards on the 105 compression stroke the gas being delivered from the cylinder C through the annular space or slot c between the cylinder body and the cylinder head, to the delivery passage F and outlet pipe F^1 .

In the construction shown in Figs. 11 to 14 the suction valves A are disposed in a circle opening downwards fitted into recesses a in the end of the cylinder body and held against their seats by springs a^1 . The delivery valve comprises a concentric ring of four ball valves B held to their seats by springs b^1 and the suction passages E and delivery passages F are formed in the cylinder head D and connect with corresponding 110 passages in the cylinder body to which the inlet pipe E^1 and outlet pipe F^1 are connected the arrangement and disposition of the valves and passages being very similar 115 to those shown in Figs. 2 and 3. Between 120 125 130

the body of the cylinder C and the cylinder head D a valve seating plate H is inserted in which seating for both suction and delivery valves are formed, with the object of obtaining valve seats in homogeneous metal where sound castings are difficult to obtain. The plate H forms the bottom of the annular suction passage E and the gas delivery passage F thus enabling the cast iron cylinder head D to be made without closed cored passages. The valve seating plate H may be made with several sets of seatings for multi-cylinder machines. The partly annular suction passage E is interrupted at h 15 where the gas delivery passage F passed across the same plane. In the arrangement shown there are two suction-passages e passing upwards through the valve seating plate H and one delivery passage f. For simplicity in machining the suction passage e and delivery passage f through the valve seating plate H are bored circular instead of being cast triangular as in Fig. 2. If the valve plate H is made of cast metal the suction 20 and delivery passages e and f therein may be cast triangular or of other suitable shape.

A valve seating plate such as H may be applied to any of the various modifications of the invention shown in the preceding figures.

In the construction shown in Fig. 15 the suction valves A⁵ and the delivery valves B⁹ are placed in the same circle around the cylinder C the suction valves in the cylinder 35 end and the delivery valves in the cylinder head D. Both sets of valves are of the conical lift type each suction valve with vertical guide pin and each delivery valve with an internal chamber into which the guide 40 pin of the suction valve projects. The suction valve lifts upwards against a spring which holds it to its seat and the delivery valve also lifts upwards and is held to its seat by a spring. The suction passages E 45 are formed in the body of the cylinder and the delivery passages F are formed in the cylinder head D with an auxiliary passage F² leading to the outlet passage F¹. The gas enters the cylinder C and the compressed 50 gas leaves the cylinder through the slot or space c between the cylinder body and the cylinder head through exhaust valve B¹⁰.

In the construction shown in Fig. 16 the suction valve comprises a single ring disc 55 valve A⁹ opening upwards set over a seating in the cylinder end and held to its seat by springs a¹ abutting against the underside of the cylinder head and the delivery valves B⁹ are disposed in a circle in the cylinder 60 head opening upwards and held against their seats by springs b¹.

The suction port or passages are formed in the cylinder body and the delivery passages in the cylinder head. The gas enters 65 the cylinders through the annular space or

slot c between the cylinder body and the cylinder head.

In this construction it will be obvious that the ring disc suction valve A⁹ may be placed in the cylinder head and also that a similar ring disc valve may be employed for a delivery valve the gas passages being arranged as required thereby.

A machine constructed as described can be driven at a sufficiently high speed to be 75 directly coupled to the shaft of an electric motor and has a minimum of clearance and a very simple arrangement of valves. Moreover it will give a large output in proportion 80 to the cost.

What I claim as my invention and desire to protect by Letters Patent is:—

1. A gas or air compressor comprising in its construction a cylinder provided with a plurality of recesses annularly disposed 85 around the cylinder end, a plurality of small light suction valves disposed therein, a cylinder head with inlet and delivery air passages therein, and a plurality of valve seats for the suction valves on the underside of 90 cylinder head.

2. A gas or air compressor comprising in its construction a cylinder provided with a plurality of recesses annularly disposed 95 around the cylinder end, a plurality of small light suction ball valves disposed therein, a cylinder head with inlet and delivery air passages therein, and a plurality of valve seats for the suction valves on the underside of cylinder head.

3. A gas or air compressor comprising in its construction a cylinder constructed with a plurality of recesses annularly disposed around the cylinder end, a plurality of small light suction valves disposed therein, a cylinder head with inlet and outlet air passages 105 therein, a plurality of valve seats on the underside of the cylinder head for the suction valves, a delivery valve and seat for the delivery valve.

4. A gas or air compressor comprising in its construction a cylinder constructed with a plurality of recesses annularly disposed around the cylinder end, a plurality of small light suction ball valves disposed therein, a cylinder head with inlet and outlet air passages 115 therein, a plurality of valve seats on the underside of the cylinder head for the suction valves, a delivery valve and seat for the delivery valve.

5. A gas or air compressor comprising in its construction a cylinder constructed with a plurality of recesses annularly disposed around the cylinder end, a plurality of small light suction valves disposed therein, a cylinder head with inlet and outlet air passages 125 therein, a plurality of valve seats on the underside of the cylinder head for the suction valves a ring of light delivery valves in the cylinder head and valve seats therefor. 130

- 4
6. A gas or air compressor comprising in its construction a cylinder constructed with a plurality of recesses annularly disposed around the cylinder end, a plurality of small 25
5 light suction ball valves disposed therein, a cylinder head with inlet and outlet air passages therein, a plurality of valve seats on the underside of the cylinder head for the suction valves, a ring of light delivery valves
10 in the cylinder head and valve seats therefor.

7. A gas or air compressor comprising in its construction a cylinder constructed with a plurality of recesses annularly disposed 30
15 around the cylinder end, a plurality of small light suction ball valves disposed therein, a cylinder head with inlet and outlet air passages therein, a valve plate interposed between the cylinder body and the cylinder
20 head, air passages therethrough, valve seats for the ball suction valves on the underside and discharge valves and seats therefor on

the upper side of said plate, inlet passages connected with the suction air passages and discharge passages connected with the discharge valves. 25

8. A gas or air compressor comprising in its construction a cylinder constructed with a plurality of recesses annularly disposed around the cylinder end, a plurality of small 35
30 light suction ball valves disposed therein, a cylinder head with inlet and outlet air passages therein, a plurality of light ball delivery valves disposed in a circle in the cylinder head, a valve plate interposed between the cylinder body and the cylinder head provided with valve seats for both sets of valves, a passage from the suction valves between the cylinder end and valve plate, inlet passages to the suction valves and delivery passages from the delivery valves. 40

In testimony whereof I have hereunto set my hand.

ARTHUR GUY ENOCK.
